UNITED STATES PATENT OFFICE.

GEORGE WRIGHT, OF OAKLAND, CALIFORNIA.

LIFEBOAT-LAUNCHING GEAR.

Application filed November 13, 1922. Serial No. 600,597.

To all whom it may concern:

Be it known that I, GEORGE WRIGHT, a citizen of the United States, and a resident of Oakland, in the county of Alameda and 5 State of California, have invented certain new and useful Improvements in a Lifeboat-Launching Gear, of which the following is a specification.

This invention appertains to certain improvements in ships' davits or life boat launching and shipping mechanisms or gears for vessels at sea, and has for its principal object to provide for a durable and efficient construction of the same whereby to 10 expedite and otherwise facilitate the shipping, launching and re-shipping of life boats, and to render the operation of the mechanisms or gears less laborious than has heretofore obtained in known types of such 15 devices.

With the foregoing and other equally important objects in view, the invention resides in the certain new and useful construction, arrangement and operation of parts as will 20 be hereinafter more fully described, set forth in the appended claims, and illustrated in the accompanying drawings, in which:—

Figure 1 is an end elevation of a preferred embodiment of the improved mechanism or 25 gear, and showing, in full lines, the position of the parts when the life boat is disposed in readiness for launching inboard of a vessel, and, in dotted lines, the position of the parts when the life boat has swung to initial 30 outboard position ready for the lowering and launching operation thereof.

Figure 2 is a front elevation of the mechanism or gear per se,

Figure 3 is an enlarged fragmentary 35 detail, partly in section, of the automatic screw actuated brake and clutch mechanism of the gear,

Figure 4 is a vertical transverse section taken on the line 4—4 of Figure 2,

Figure 5 is a side elevation, partly in section, of a modified form of the mechanism or gear, and,

Figure 6 is a vertical transverse section taken on the line 6—6 of Figure 5.

Referring to the drawings, wherein similar characters of reference designate corresponding parts throughout the several correlated views thereof, and more particularly to Figures 1 to 4, inclusive, the preferred embodiment of the invention is shown 50 therein as it appears when installed in posi-

tion on the boat or other deck *a* of a vessel whose hull is indicated as at *b*. Spaced inwardly from the side of the hull *b*, and rising from the deck *a*, are a pair of standards 60 10, only one of which is shown in the present instance, having davits 11 pivoted, as at 12, from the upper ends thereof for swinging movements from normal vertical position in-board of the vessel to inclined position out-board of the side of the hull *b*, of the latter, substantially as shown in full and dotted lines in Figure 1. A life boat *c* is suspended between the standards 10 and the davits 11 65 from the ends of cables or falls 13 trained 70 through blocks 14 carried at the extreme outer ends of the davits, and is supported against swinging movements on rest blocks *d*.

Disposed inwardly of the davits 11 is a 75 winch gear frame formed of spaced standards 15 and 15', which are connected at their upper ends by a rod bolt 16. Journalled through the standards 15 and 15', at 80 a distance below the rod bolt 16, is a shaft 17 on which is keyed, as at 17', a double winch drum 18 around the individual drum sections of which are wound the other ends of the cables or falls 13. This drum 18 is 85 preferably mounted on the rear half portion of the shaft 17, inwardly of the standard 15', and has its forward flanged end formed with or otherwise secured to a solid member 19 which acts in the manner of a combined fly-wheel and brake drum. This wheel or 90 drum 19 has trained around its periphery a 95 brake band 20, while its outer forward face is adapted to be acted upon by an annular brake member 21, as will be hereinafter more fully explained.

Loosely mounted for normally free rotation on the shaft 17, forwardly of the drum 18, is a screw 22 which has its rearwardly disposed end formed to provide an enlarged portion 23. The outer end face of this portion 23 is provided with a plurality of clutch lugs or teeth 24 arranged to be moved into and out of engagement with a corresponding number of clutch recesses 25 formed in the opposed end face of a hub portion 26 of the 100 brake drum 19. The inner or forward end of the enlarged portion 23 is formed to provide an annular flange 23', the rear side of which is abutted by a circular collar 27 loosely mounted on the portion 23. The 105 collar 27 is held in its abutting relation with the flange 23' by means of a coiled spring 28,

which encircles the portion 23 and the hub portion 26. Enclosing the end portion of the spring 28 surrounding the hub 26 is a cylindrical housing 26', which may, if desired, be formed as an integral part of the latter, as shown in Figure 3, while the outer end portion of the spring 28 is housed within an annular recess or seat 27' formed inwardly of the outer face of the collar 27. The outer 10 end portion of the annular recess or seat 27' is enlarged to a greater diameter than that of the spring seating portion thereof, and is arranged in overlapping relation with respect to the opposed end portion of the 15 housing or flange 26', whereby the spring 28 is completely enclosed for protection against injury. Projecting diametrically at the upper and lower sides of the collar 27 are ears 29 to which are pivoted at one of their 20 ends the arms 30, the same having their other ends similarly pivoted to link members 31. These link members 31 are bolted at their opposite ends, as at 31', to brace members 32 which are, in turn, secured to stationary parts of the gear supporting frame, 25 as at 32'.

Mounted on the screw 22 is a travelling nut or collar 33, which is formed to provide a plurality of radially disposed ears 33' to which are pivoted arms 34 extending to and through the link members 31 for pivotal connection with ears 21', formed on the outer face of the annular brake member 21, whereby the latter will be moved into and 30 out of operative braking relation with respect to the opposed face of the drum or wheel 19 correspondingly with the movements of the nut or collar 33 along the screw 22.

40 The action of the spring 28 is to normally force the screw 22 forwardly along the shaft 17, so that the clutch lugs 24 are disengaged from the clutch recesses 25 of the hub 26, and whereby the brake drum or wheel 19 and the drum 18 will be disconnected from the screw 22 and free for rotation with the shaft 17. However, to obtain a desired automatic operation of the brake member 21, during certain of the rotative movements of the drum 18, the screw 22 is to be forced rearwardly along the shaft 17 for the engagement of the clutch lugs 24 carried thereby with the clutch recesses 25 of the hub 26, by means of a wedge block or shoe 35, 45 which is arranged to be forced against a collar 36 carried at the forward end of the screw 22 for the purpose. This block or shoe 35 is preferably in the form of a wedge having a bevelled face at its inner end for cooperation with a similarly bevelled face formed on the forward side of the collar 36, and, at its forward or outer end, with a straight flat face arranged to bear against the inner side of the standard 15. This 50 wedge block 35 is to be readily manipulated

through the medium of a hand lever 37 pivoted to the standard 15 above the bearing 15' thereon, as at 38, and is carried on an angularly extended arm 37', formed at the lower pivoted end of the lever 37 for the purpose, and whereby to be lowered and raised to and from operative position correspondingly with the swinging movements of the lever and arm.

For imparting the desired or necessary rotative movements to the shaft 17, a relative large gear 39 is loosely mounted on the forward end thereof, which end is projected for a distance through the standard 15 for the purpose, and also to have slidably 70 keyed thereon at its extreme free end a clutch member 40 arranged to be moved into and out of engagement with a complementary clutch element 41 carried at the outer end of the hub of the gear 39. The gear 39 is 75 arranged in mesh with a driving pinion 42, which is keyed on a stub shaft 43 journalled at its inner end through the standard 15 at a point above the gear 39 and has its outer end projecting through a guard frame 44, secured at the forward side of the standard 15, 80 for the reception thereon of a hand crank 45. The clutch member 40 is to be readily operated to connect and disconnect the gear 39 to and from the shaft 17, by means of a 85 hand lever 46, which is pivoted to the same, as at 40', and to a bracket 47 projecting from the forward side of the guard frame 44. To lock the hand lever 46 in position to 90 keep the clutch members 40 and 41 engaged the handle portion of the lever 46 is provided with an opening 48 to be registered with an opening 48', formed in the outer end of a keeper bracket 49 projecting from the forward side of the guard frame below 95 the bracket 47, when a lock pin 50, carried at the end of a chain 51 attached to the bracket 49, will be inserted through the openings for the purpose.

The brake band 20, hereinbefore spoken of as being trained around the periphery of the brake drum or wheel 19, has one of its ends secured, as at 52, to the upper end of a bracket 53, which is securely fastened to the deck *a* of the vessel at the outboard side of 110 the mechanism or gear, substantially as shown in Figures 2 and 4, while its other end is similarly attached, as at 54, to the outer end of an angularly disposed arm or extension 55, formed at the lower end of a 115 lever 56, which is pivotally mounted in the bracket 53, as at 56'. This lever 56 is of a length to normally incline upwardly, so as to have its free end overlie the life boat *c*, when the latter is either in its position of 120 readiness for launching on ship-board or in its initially suspended position out-board of the vessel, as is clearly illustrated in Figure 1. The extreme outer end of the lever 56 is 125 provided with an eye 57 for the securing 130

therein of one end of an operating rope or cable 58, which has its major length normally coiled, in the bottom of the life boat *c*, and in a manner to readily pay out during the lowering movement of the latter.

In the operation of the foregoing embodiment of the invention, and it is desired to effect the launching of the life boat *c*, the hand lever 37 is moved to its full line position (Figure 2) to force the wedge block 35 home between the bearing 15^a and the collar 36, when the screw 22 will be moved rearwardly along the shaft 17 for the engagement of the clutch lugs 24 thereof in the recesses 25, whereby the screw 22 will be coupled to the brake drum 19, the winch drum 18 and the shaft 17. The hand lever 46 will now be manipulated to move the clutch 40 into engagement with the clutch 41 to couple the gear 39 to the shaft 17, when, by turning the hand crank 45 in an out-board direction, the shaft 17 will be rotated, together with the drum 18, the brake drum 19, and the screw 22, with the result that the life boat *c* will be lifted from the rest blocks *d*, and the brake member 21 released from its braking effect on the brake drum 19, the cables or falls 13 being further wound upon the drum 18, and the collar or nut 33 being moved forwardly along the screw 22 for the purpose. Now, by a reversed movement of the hand crank 45, the cables or falls 13 will slack off to admit of the outward swinging of the davits 11 for the moving of the life boat *c* to initial out-board position, during which slackening off of the cables or falls 13, and as a consequence of the reversed rotation of the shaft 17, the drum 18, the brake drum 19 and the screw 22, the nut or collar 33 will move rearwardly of the latter and will again engage the brake member 21 with the opposed face of the brake drum 19, so that the life boat *c* will be held in its initially suspended out-board position until it is desired to lower the same to its water-borne state. A member of the crew of the life boat *c*, remaining on board the vessel for the purpose, will now manipulate the hand lever 37 to withdraw the wedge block 35 from its holding engagement with the collar 36 of the screw 22 for the automatic disengagement of the clutch members or lugs 24 of the latter from the clutch recesses 25 of the brake drum 19 and the release of the brake member 21, also from the opposed face of the brake drum 19, while, at the same time, a member of the crew within the life boat *c* will grasp the hand rope or cable 57 and exert a downward pull on the lever 56 to tighten the brake band 20 around the brake drum 19, so that the life boat will be held against lowering movement by gravity until after the remaining member of the crew has taken his place on board. The life boat *c* will now lower by gravity upon a slackening up

on the hand rope or cable 57 for the loosening up of the brake band 20 on the brake drum 19, when the drum 18, the brake drum 19 and the shaft 17 will freely rotate in the standards 15, 15', for the unwinding of the cables or falls 13. With the life boat *c* fully water-borne, the attached ends of the cables or falls 13 will now be cast off from the opposite ends thereof, when the same will be ready to get under way.

In Figures 5 and 6, there is shown a modified form of the invention, and, in this instance, the same is power operated, so as to be controlled entirely by a member of the crew of the life boat *c* and from a position therein. As shown, a base 59 is provided and has the standards 15^a and 15^b rising from the opposite ends thereof, with the shaft 17^a journalled at its opposite ends therethrough, somewhat after the manner of the preferred form of the winch gear. Fastened on the shaft 17^a, immediately inward of the standard 15^a and by means of a key 17^b, is a double drum 18^a, around the two sections of which are wound the cables or falls 13^a. Keyed on the shaft 17^a, and immediately inward of the standard 15^b, is a brake drum or wheel 19^a, having its periphery encircled by a brake band 20^a. Overhanging the brake drum 19^a is an arm 15^c, which is angularly formed with the upper end of the standard 15^b, and is of a length to have its free end project for a short distance beyond the plane of the inner face of the drum, whereby to have bolted thereto, as at 60, a depending bracket 61, which is formed to provide a thickened bearing portion upwardly from its lower end for the journaling therein of an intermediate portion of the shaft 17^a.

Loosely mounted on the shaft 17^a, immediately in rear of the winch drum 18^a, is a worm gear or wheel 22^a arranged in mesh with a worm 22^b keyed on the shaft of a motor M, which is bolted in position on the base 59. The hub of the worm gear or wheel 22^a, at the rear side thereof, is formed to provide for a set of clutch recesses 25^a, with which are cooperative a corresponding number of clutch lugs or teeth 24^a of a clutch member 24^b, keyed for sliding movement on the shaft 17^a. Interposed between the rear end of the clutch member 24^b and the opposed face of the bearing portion of the bracket 61, is a coiled spring 28^a, normally acting to tension the clutch member 24^b into engagement with the worm gear or wheel 22^a, whereby the power from the motor M will be transmitted to the shaft 17^a, and consequently, to the winch drum 18^a and the brake drum or wheel 19^a. For effecting the disengagement of the clutch 24^b from the complementary clutch portion of the worm gear or wheel 22^a, a lever 62 is pivoted at an intermediate point to the clutch 24^b, and at

its lower end to an angularly disposed arm 61^a formed at the lower end of the bracket 61.

In controlling the operation of this type 5 of the gear, it is contemplated that only one member of the crew of the life boat will be required for the purpose, and, to such end, the operating devices of the brake band 20^a and the clutch 24^b are interconnected in a 10 manner to be hereinafter more fully explained. The brake band 20^a has one of its ends secured, as at 54^a, to the angularly bent lower end portion 55^a of an operating lever 56^a, and the other of its ends to the pivotal 15 connection 56^b of the lever 56^a with the bracket 53^a, which is secured on the base 59. This operating lever 56^a is interconnected for simultaneous operation with the clutch lever 62, by means of a hand cable or rope 20 58^a which has one of its ends trained through an eye 57^a, formed at the upper end of the lever 56^a, and from thence through an eye 61^b formed at one side of the bracket 61, and then through an eye 62^a formed at the upper 25 end of the lever 62, where it is knotted against all possibility of being pulled out of engagement with the latter eye. Clamped on the cable or rope 57^a, at a suitable point thereon between the eye 56^a of the lever 56, 30 and the eye 61^b, of the bracket 61, is a metal collar 63, which will engage the end of the lever 56^a to operate the same, when the free end of the cable or rope 58^a is pulled on from within the life boat c.

35 In the operation of this modified form of the invention, a member of the crew of the life boat will board the same and take hold of the cable or rope 58^a, when the remainder of the crew will go abroad, the last man 40 stopping only long enough to start up the motor. Upon the initial starting of the motor M, the worm gear or wheel 22^a will rotate and through the clutch 24^b will, in turn, rotate the shaft 17^a, the winch drum 18^a, and the brake drum 19^a, with the result 45 that the life boat will be lifted from its point of rest for a slight distance. The member of the crew of the life boat, having charge of the cable or rope 58^a, will now 50 exert a pull on the same for the operation of the lever 62 to disengage the clutch 24^b, when the worm gear or wheel 22^a will continue to rotate freely on the shaft 17^a, while the shaft 17^a, the drum 18^a, and the brake 55 drum 19^a will be free to be rotated in the opposite direction under the unwinding action of the cables or falls 13^a caused by the lowering of the life boat by gravity. This 60 lowering movement of the life boat may be readily checked, if necessary, by a greater pulling action being exerted on the cable or rope 58^a for the full compression of the spring 28^a, which readily admits of the tightening of the brake band 20^a on the 65 brake drum 19^a, but which does not need

to be fully compressed to allow for the disengagement of the clutch, as hereinbefore stated. With the clutch disengaged, and the spring 28^a only partially compressed, the brake band 20^a is not tightened on the 70 brake drum 19^a sufficiently to prevent the desired gravitation of the life boat to water-borne position, but only to effect a retardation of the lowering movement thereof.

From the foregoing, it will be obvious 75 that, while preferred embodiments of the launching mechanisms or gears have been described and illustrated herein in specific terms and details of construction, arrangement and operation, various changes in and other modifications thereof may be resorted to, without departing from the spirit of the invention, or the scope of the claims appended hereto.

Having thus fully described the invention, what is claimed, is:—

1. The combination with the davits of a vessel, of a falls normally acting to suspend a life boat from the davits and in a position of readiness for launching inboard of the vessel, a winch drum for said falls, an actuating means for said winch drum, means for disconnecting said actuating means from said winch drum for the lowering of the life boat to water-borne position by 90 gravity, and automatic means for braking said winch drum prior to the final lowering movement of the life boat.

2. The combination with the davits of a vessel, of a falls normally acting to suspend a life boat from the davits and in a position of readiness for launching inboard of the vessel, a winch drum for said falls, means normally braking said winch drum against rotative movement, means for actuating said winch drum for the initial step in the lowering movement of the life boat out board of the vessel, means for automatically releasing said braking means simultaneously with the operation of said actuating means, and means for disconnecting said actuating means from said winch drum for the further lowering of the life boat to water-borne position by gravity.

3. The combination with the davits of a vessel, of a falls normally acting to suspend a life boat from the davits and in a position of readiness for launching inboard of the vessel, a winch drum for said falls, means normally braking said winch drum against rotative movement, means for actuating said winch drum for the initial step in the lowering movement of the life boat out-board of the vessel, means for automatically releasing said braking means simultaneously with the operation of said actuating means, said braking means being automatically actuated to subsequent operative position for holding said winch drum against further rotative movement when the 115 120 125 130

life boat has reached its initially lowered position, and manually actuated means for effecting the further release of said braking means from said winch drum for the lowering of the life boat to water-borne position by gravity.

4. The combination with the davits of a vessel, of a falls normally acting to suspend a life boat from the davits and in a position of readiness for launching inboard of the vessel, a winch drum for said falls, means normally braking said winch drum against rotative movement, means for actuating said winch drum for the initial step in the lowering movement of the life boat out-board of the vessel, means for automatically releasing said braking means simultaneously with the operation of said actuating means, said braking means being automatically actuated to subsequent operative position for holding said winch drum against further rotative movement when the life boat has reached its initially lowered position, manually actuated means for effecting the further release of said braking means from said winch drum for the lowering of the life boat to water-borne position by gravity, and a second means for braking said winch drum for controlling the final lowering movements of the life boat.

5. The combination with the davits of a vessel, of a falls normally acting to suspend a life boat from the davits and in a position of readiness for launching inboard of the vessel, a winch drum for said falls, 35 means normally braking said winch drum against rotative movements, means for actuating said winch drum for the initial lowering step in the movement of the life boat out-board of the vessel, means for automatically releasing said braking means simultaneously with the operation of said actuating means, said braking means being automatically actuated to subsequent operative 40 position for holding said winch drum against further rotative movement when the life boat has reached its initially lowered position, manually actuated means for effecting the further release of said braking means from said winch drum for the lowering of the life boat to water-borne position by gravity, a second braking means cooperative with said winch drum for controlling the final lowering movement of the life boat, and means for controlling said last 45 mentioned braking means from within the life boat throughout the final lowering movements thereof.

GEORGE WRIGHT.
